Patented Jan. 10, 1922.

UNITED STATES PATENT OFFICE.

ADOLPH FLICK, OF DEER PARK, AND OSCAR VAN KIRK, OF CINCINNATI, OHIO.

WATER HEATER.

1,402,925.

Specification of Letters Patent. Patented Jan. 10, 1922.

Application filed March 1, 1920. Serial No. 362,625.

To all whom it may concern:

Be it known that we, ADOLPH FLICK and OSCAR VAN KIRK, citizens of the United States of America, and residents of Deer Park and Cincinnati, in the county of Hamilton and State of Ohio, have invented 5 a new and useful Improvement in Water Heaters, of which the following is a specification.

10 An object of our invention is to provide a water heating device that may be easily, readily and economically installed and connected with a faucet.

Our device is for use (especially for domestic use) where there is no hot water faucet, but merely one faucet, to which my appliance can be attached, thereby providing a means to have both hot or cold water from such one faucet.

20 These and other objects are attained by the means described herein and disclosed in the accompanying drawings, in which:—

Fig. 1, is a side elevation of a water system embodying our invention.

25 Fig. 2, is a cross section of the coupling connections forming a detail of our invention.

Fig. 3, is a plan view of the heating element forming a detail of our invention, on 30 line 3—3 of Fig. 1.

Fig. 4, is a front elevation of the regulator forming a detail of our invention.

Fig. 5, is a sectional view on line 5—5 of Fig. 1.

35 Fig. 6 is a sectional view on line 6—6 of Fig. 5.

Our invention consists of a heating chamber or drum A connected with a series of pipe links B through which water is directed 40 to and from the drum. A heating element D is disposed below the drum. A series of couplings E are attached to the primary faucet F in such relation that a flow of water may be directed to either the drum or boiler 45 or to a secondary or cold water faucet F'.

The three way coupling e is secured to an ordinary faucet F by any suitable means such as screw flange e' and registers with one of the ways. By means of similar screw 50 flanges a secondary faucet F' is attached to coupling e and registers with one of the ways. A pipe b registers with the other way of coupling e and directs a flow of water to the boiler A. Regulator H is disposed in the 55 pipe b at a place between the coupling e and

the boiler. Spray K is attached to pipe b and extends inside the boiler.

Spray K is a form of nozzle having a series of radial ducts k extending from its center to its periphery and communicating with the bore in the pipe and the interior of boiler A. The passages are adapted to direct the water in a fine spray or stream horizontally through the boiler to the circumscribing wall a of the boiler. Screw flange 65 b' and lugs a⁹ secure the top a⁷ upon the boiler and permit ready access to the interior of the boiler when disengaged.

The boiler has a removable top a⁷ and hood a⁸. About the sloping wall a is formed 70 flange a¹⁰ adapted to return any splashing spray to the wall and prevent leakage. The hood a⁸ having vents a⁶ and supporting flange a¹¹ engaging top a⁷, serves to confine the heat about the wall and bottom of the 75 boiler.

A series of radially extending flanges or panels a' divide the section of the boiler A, below the nozzle, into a series of compartments a². A series of arcuate ribs a³ in each 80 compartment extend alternately from opposite panels leaving a small space or exit between the end of the rib and the panel toward which they extend. A common drain or exit a⁴ is provided whereby the water in the several compartments drains into the pipe b' directing the water back to hot water exit G adjacent to the faucets F and F'. The pipe b' is secured by flange e' to the coupling e, thereby making a neat and compact arrangement for hot and cold water discharge appliances. 85

A heating element D is secured below the boiler. A stop-cock or valve d is used to modify the flow of gas passing to burner d' 95 from supply pipe d².

The regulator H consists of a valve having a handle h by means of which the valve is operated. The handle serves as an indicator registering upon a plate h' upon which 100 may be inscribed the words "Hot," "Cold," "On," "Off," or similar terms to acquaint the user with the proper manipulation of the regulator.

The operation of the device is as follows:— 105

The regulator valve H and secondary faucet F' are normally closed, the primary faucet F is kept open. When cold water is wanted it is run out of the faucet F'. When 110

hot water is wanted the regulator handle h is moved to the proper position, either hot or warm, etc. The water pressure is modified by the regulator H . The water will 5 flow through the pipe b to the nozzle K . The ducts k are comparatively small in relation to the pipe b , whereby the water will be thrown to the outer wall a of the boiler A in a spray or fine stream. The floor or 10 bottom a^1 of the boiler is slightly conical on its inner surface. The water sprayed against the wall a must then follow a circuitous path among the ribs to reach the center of the boiler where the common exit a^4 permits the water to pass off through the 15 pipe b' . As the water follows the circuitous path or way over the floor of the boiler it is heated. The pressure with which the water is forced through the spray determines the 20 quantity of water that will pass through the boiler in a given period of time. Accordingly, regulating this flow by the valve H will vary the degree to which the water's temperature will be raised, a lesser flow of 25 water becoming hotter than a greater flow.

The heating element may be operated by lighting the burner d' whenever the device is to be used, or by leaving it burn continuously.

What we claim is:—

1. In a water heating device a boiler comprising a tank, a series of vertical flanges extending radially through the tank and forming therein compartments and having a common discharge at their center and arcuate ribs between the flanges and extending vertically from the bottom of the tank and having a continuous circuitous way, formed by the ribs, extending from the outer wall of the tank to the common discharge. 35

2. In a water heating device the combination with a boiler comprising a tank, a series of vertical flanges extending radially through the tank and forming therein a series of compartments having a common 45 discharge at their center, and arcuate ribs between the flanges and extending vertically from the bottom of the tank and having a continuous circuitous way, formed by the ribs, extending from the outer wall of the 50 tank to the common discharge, and of means adapted to direct water to the circuitous way at the outer wall of the tank.

In witness whereof, we have hereunto subscribed our names this 25th day of February, 1920. 55

ADOLPH FLICK.
OSCAR VAN KIRK.
